UNITED STATES PATENT OFFICE.

ARTHUR C. GROVER, OF WILLOUGHBY, OHIO, ASSIGNOR OF ONE-HALF TO
EDWARD J. DICKEY, OF SAME PLACE.

COMBINED CAR AND PIPE COUPLING.

SPECIFICATION forming part of Letters Patent No. 449,219, dated March 31, 1891.

Application filed April 3, 1890. Serial No. 346,424. (No model.)

To all whom it may concern:

Be it known that I, ARTHUR C. GROVER, of Willoughby, in the county of Lake and State of Ohio, have invented certain new and useful Improvements in Combined Automatic Car and Pipe Couplers; and I do hereby declare the following to be a full, clear, and exact description of the invention, such as will enable others skilled in the art to which it pertains to make and use the same.

My invention relates to improvements in a combined automatic car and pipe coupler; and it consists in certain features of construction and in combination of parts hereinafter described, and pointed out in the claims.

In the accompanying drawings, Figure 1 is a side elevation, in section, through the center of the device. Fig. 2 is an end elevation, in section, on line $x x$, Fig. 1. Fig. 3 is a side elevation of the coupling-bar detached. Fig. 4 is a side elevation of member B detached. Fig. 5 is a side elevation of member E detached.

A represents the draw-bar connected in the usual manner with the car. This bar, as shown in Fig. 2, is round; but this is not material, as the draw-bar may be square or rectangular in cross-section, if preferred. The outer end of the draw-bar is flaring, as shown at A', and has a vertical hole A² for receiving an ordinary coupling-pin, if need be. The draw-bar has also a vertical slot or recess for receiving the coupling-slide B. The draw-bar has slots a a and a slot a', and has depending ears a² a², located on either side of slot a', for purposes hereinafter mentioned.

C is the coupling-bar, the same being round in cross-section and provided at either end with enlarged and approximately spherical heads C', with square shoulders at c'. The coupling-bar has a central hole c of sufficient size for the purpose, and extending the entire length of the coupling-bar.

D is a sliding head or follower adapted to fit easily inside the head or draw-bar, and in case the draw-bar and head are round, this head is prevented from turning by means of pin D', projecting from the head and operating in slots a a of the draw-bar. The outer face of the head D or attachment of the

latter, as the case may be, has a semi-spherical depression D², adapted to fit the head of the coupling-bar, so as to constitute a ball-and-socket joint. Head D is provided with short outwardly-projecting pins d³. As head 55 D is usually of cast-iron, some better material should be provided for engaging the coupling-pin, and hence I prefer to chamber head D and to fit the chamber with, for instance, a block D³ of comparatively hard rubber, or 60 in place of rubber bronze, brass, or whatever material may be found most practicable for the purpose.

I have reduced my invention to practice in an experimental way, employing a rubber 65 block D³ that serves the purpose well. A pipe d connects with head D, the pipe extending with an easy fit through a hole in cross-bar a³ of the draw-bar. Between the cross-bar and head D is located a spiral 70 spring d', the spring being coiled around the pipe and bearing against the head and the cross-bar, the action of the spring tending to force head D outward, so as to make a tight joint at the ball-and-socket bearing aforesaid. There is a central opening through head D and block D³, so that there is always open communication between pipe d and bore c of the coupling-bar B, and as the coupling device is supposed to be alike on opposing ears, 80 air, steam, or fluid of any kind, as the case may be, may be passed from one car to the other through the coupling-bars. When the cars are not coupled, the engagement of pins D' D' with the forward end wall of slot a 85 limits the movement of head D in this direction. To pipe d is attached a piece of flexible pipe or hose d², the latter being supposed to connect, for instance, to the supply-pipe of the air-brake. The gravity coupling-slide B 90 (shown in detail in Fig. 4) has a recess or opening B', adapted to embrace with an easy fit the coupling-bar C, and has a larger opening B², adapted to receive loosely the head C' of the coupling-pin. Member B has internal 95 square shoulders b and is provided with short pins b' b', and has a hook, staple, ear, or other suitable device at b² for attaching, for instance, a lever, chain, or whatever may be used for elevating slide B in uncoupling the 100

cars. When the cars are coupled, pins d^3 come close to but do not engage slide B; but when slide B is elevated and the cars are uncoupled, head D is advanced by the action of 5 spring d' , so that pins d^3 extend under shoulder b and hold slide B in its elevated position.

Slide B cannot easily be drawn up while there is a draft on the coupling-bar, and it 10 is customary to back the engine to loosen these slides. If, therefore, the operator under such conditions should elevate slide B he would have to hold it elevated until such time as the cars were so far separated that 15 head D could advance and lock slide B by means of pin d^3 . To remedy this difficulty, so as not to delay the operator, who might likely wish to uncouple several cars while the engine was backed, I provide a gravity-arm 20 E, pivoted at e to and between ears a^2 aforesaid. The arm, as shown in Fig. 5, has a tongue E', that extends through a slot a' in front or outside of head D. Arm E has shoulders e' , adapted to engage the under side of 25 pins b' when the parts are in position with slide B elevated and with arm E in approximately vertical position maintained by gravity. Now when the cars are pushed together for uncoupling, head D will have been backed 30 or moved inward, and hence does not hold lever E in its tilted position, and when slide B is elevated arm E is snubbed back by pins b' , but immediately swings forward again, so that shoulders e' engage pins b' and hold 35 slide B elevated. The operator can now go about his business, and when the cars draw apart, so that head D again advances and tilts lever E, the arrangement is such that pins d^3 engage shoulders b just before shoulders e' are disengaged from pins b' .

In coupling the cars, as the bumpers of the cars come together, so that coupling-bar C pushes back head D and thereby releases slide B, the slide falls by gravity and locks 45 bar C. When slide B is elevated, whereby shoulders b rest on pins d^3 , the bottom of pins b' are about on a line with shoulders e' —say an eighth of an inch, more or less, apart—and when slide B has descended something 50 less than a quarter of an inch shoulders e' cannot engage pins b' , and the slide will fall this distance before arm E has time to swing forward. When one end of the coupling-bar is in position, the cars being uncoupled by

reason of the pressure of head D on the coupling-bar, shoulders e' of the bar engage slide B with sufficient force to hold the coupling-bar in approximately a horizontal position, so that the free end thereof will always enter the opposing coupler. 55 60

What I claim is—

1. A combined automatic car and pipe coupler comprising a hollow coupling-pin having rounded enlarged head, a draw-bar having an internal spring-actuated head adapted to engage the rounded ends of such coupling-bar, and a gravity coupling-slide adapted to lock the coupling-bars, substantially as set forth. 65

2. The combination, with hollow coupling-bars having enlarged semi-spherical heads, of a draw-bar having an internal spring-actuated head adapted to engage the coupling-bar, forming a ball-and-socket joint therewith, said head having a pipe attachment in open relation with the bore of the coupling-bar, and a gravity coupling-slide adapted to lock the coupling-bar, substantially as set forth. 70 75

3. The combination, with a hollow coupling-bar having enlarged rounded heads, and a draw-bar having an internal spring-actuated head adapted to engage such coupling-bar, such head being provided with forwardly-projecting pins, of a gravity coupling-slide having recessed sections adapted, respectively, to engage the coupling-bar and to admit the head of the coupling-bar, such coupling-bar having internal shoulders adapted to engage and rest on the pins of the head for holding the coupling-slide elevated, substantially as set forth. 80 85 90

4. The combination, with hollow coupling-bar and draw-bar having an internal spring-actuated sliding head having a seat adapted to engage the head of the coupling-bar, of a gravity-arm pivoted to and depending from 95 the draw-bar and having a tongue extending inside the draw-bar in advance of the sliding head, and a gravity coupling-slide having pins to engage the shoulders of such gravity-arm for holding the slide elevated, substantially as set forth. 100

In testimony whereof I sign this specification, in the presence of two witnesses, this 15th day of March, 1890.

ARTHUR C. GROVER.
